UNITED STATES PATENT OFFICE

GLENN E. McFADDEN, OF DETROIT, MICHIGAN, ASSIGNOR TO LINCOLN MANUFACTURING COMPANY, OF DETROIT, MICHIGAN, A CORPORATION OF MICHIGAN

DESIGN FOR A CHANDELIER OR ANALOGOUS LIGHTING FIXTURE

Application filed July 22, 1929. Serial No. 32,159. Term of patent 7 years.

To all whom it may concern:

Be it known that I, GLENN E. McFADDEN, a citizen of the United States, residing at Detroit, county of Wayne, State of Michigan, have invented a new, original, and ornamental Design for a Chandelier or Analogous Lighting Fixture, of which the following is a specification, reference being had to the ac-

companying drawing, forming part thereof.

The figure of the drawing is a perspective of my improved chandelier or analogous lighting fixture.

I claim:

The ornamental design for a chandelier or analogous lighting fixture, as shown.

GLENN E. McFADDEN.
